UNITED STATES PATENT OFFICE.

WALTER S. JARBOE, OF ALLEGHENY, PENNSYLVANIA, ASSIGNOR, BY MESNE ASSIGNMENTS, TO THE NATIONAL WRAPPING-MACHINE COMPANY, OF PENNSYLVANIA.

PACKAGE-WRAPPING MACHINE.

SPECIFICATION forming part of Letters Patent No. 394,772, dated December 18, 1888.

Application filed March 26, 1887. Serial No. 232,577. (No model.)

To all whom it may concern:

Be it known that I, WALTER S. JARBOE, a citizen of the United States, residing at Allegheny, in the county of Allegheny and State 5 of Pennsylvania, have invented certain new and useful Improvements in Package-Wrapping Machines; and I do hereby declare the following to be a full, clear, and exact description of the invention, reference being 10 had to the accompanying drawings, which form part of this specification.

In Letters Patent No. 367,637, granted August 2, 1887, I have described a package-wrapping machine wherein the paper which 15 is to form the wrapper is intermittently fed to a pair of shears, which cut off a sheet of a size adapted to enfold the article to be wrapped, the sheet so cut off being then manipulated and automatically folded over and 20 around and in at the ends of the article being wrapped by means of certain peculiar mechanism and moving parts operated from a common shaft.

My present invention has relation to package-wrapping machines, and is designed as an 25 improvement on the machine described and shown in my aforesaid application for Letters Patent, and embraces many of the essential features of that application, as well as certain new and novel features which will be 30 hereinafter fully described and claimed.

In the following description I will refer as briefly as is consistent with a full and clear understanding of my present invention to the 35 portion of the apparatus already described and shown in my before-mentioned pending application, and will more specifically describe those parts which I believe to be new.

My present invention has for its object the 40 provision of novel means for automatically wrapping packages or blocks of solid material in paper or other flexible material.

My invention has for its further object the provision of means for automatically wrapping articles, packages, or blocks of solid material in a double wrapping of paper or other flexible substance—that is, two separate sheets or sections of paper or other suitable material one over the other at a single operation.

My invention has for its still further object the provisions of means in a package-wrapping machine for readily adjusting the machine to wrap packages, blocks, or articles of different sizes.

My invention has for its still further object the provision of novel means comprising the peculiar construction, combination, and arrangement of parts hereinafter described for more rapidly, accurately, and neatly enfold- 55 ing and wrapping packages than has heretofore been possible.

My invention therefore consists in the construction, combination, and arrangement of parts more fully described hereinafter, and 60 specifically pointed out in the claims.

Referring to the accompanying drawings, Figure 1 is a perspective view of my improved wrapping-machine; Fig. 2, a side elevation of the same; Fig. 3, a plan view of the same; 70 Fig. 4, a plan view on a larger scale of the framing of the folding devices; Fig. 5, a detail view showing one of the movable plates which support the article previously to its being wrapped; Figs. 6 and 7, sectional views 75 of the supporting-plates and their appurtenant parts; Fig. 8, a plan view of the side-wing folders; Fig. 9, a plan view of the paper-supporting forks and the device for operating the same; Fig. 10, a side elevation of the 80 same; and Fig. 11, a plan view of a portion of the bottom of the table of the machine, showing the devices for adjusting the side-angle folders. Fig. 12 is a vertical transverse sectional view on line $x x$ of Fig. 2. Fig. 13 85 is a perspective view of the side-folders and operating mechanism. Fig. 14 is a vertical longitudinal section, on enlarged scale, of that portion of the machine which embraces the folding appliances. Fig. 15 is a transverse 90 sectional view, on enlarged scale, of the upper part of the machine on the line $z z$ of Fig. 14. Fig. 16 is a series of views representing a package in different stages while being enfolded.

a designates the table upon which the working parts of the machine are mounted, and *a a* the legs supporting the same.

B designates the main or driving shaft of the machine, suitably journaled in bearings 100

b b, sustained by the legs *a a*, and carrying the cam-wheels *B' B³*, the mutilated gear-wheel *B²*, and the band-wheel *B⁴*, through which and a crank, *B⁵*, on the end of the shaft motion is communicated to the working parts of the machine.

Upon vertical arms *c c* and horizontal arms *c' c'* at one end of the table *A* are respectively journaled two rolls or reels of paper or other material suitable for enfolding the article to be wrapped, said rolls or reels being lettered *C C'* and sustained on shafts *c² c³*.

The strips of paper or other wrapping material from the rolls *C C'* are designated *d e*, and each strip passes through a pair of feed-rolls constructed and operating in the manner of the feed-rolls employed for a like purpose in my before-mentioned Letters Patent—that is, each pair of feed-rolls consists of a large roll intermittently operated by means of a dog upon a reciprocating arm taking into teeth upon a wheel fixed on the shaft of the roll, and a spring-stop, *e⁷*, and a smaller roll mounted in an elastic bearing, the paper passing between the rolls and being fed positively but intermittently forward by their motion.

D designates the upper and smaller feeding-roll for the strip *d*, journaled in bearings *D' D'*, rising from the table *A*, the journals of said roll being pressed upon by springs fitted in sockets *d' d'*, and *D²* designates the lower feed-roll mounted on a shaft, *d²*, that is journaled in hangers *d³ d³* on the bottom of the table *A*. The shaft *d²* projects beyond the hanger on one side, and to the projecting end of the shaft is secured a wheel, *D³*, having teeth *d⁴ d⁴ d⁴ d⁴*, with which engages a spring-dog, *d⁵*, on an arm, *d⁶*, loosely mounted on the shaft. The end of the arm *d⁶* is pivotally attached to the lower end of a vertical rod, *d⁷*, which is pivotally attached at or about its middle to a curved pitman-rod, *d⁸*, connected at its other end to the crank *B⁵* on the end of the main driving-shaft *B*.

B designates the larger feeding-roll for the strip *e*, mounted on a shaft, *e²*, journaled in standards *E' E'*, and having a wheel, *E³*, with teeth *e⁴ e⁴ e⁴ e⁴*, a pivoted arm, *e⁶*, carrying a dog, *e⁵*, and pivotally secured to the end of the vertical rod *d⁷*.

E² designates the smaller feed-roll of strip *e*, journaled in the standards *E' E'* and sustained on springs in sockets *e' e'*. The feed-roll *D²* of the strip *d* is, it will be observed, somewhat larger than the feed-roll *E* of strip *e*, and by reason of this difference in the size of these rolls the strip *d* will be fed forward a somewhat greater distance than the strip *e* at each downward movement of the vertical rod *d⁷*.

The several rolls *D E D² E²* are grooved, and guiding-wires *f f' f' f'* on frames *F* and *F'* project through the grooves and serve to guide the strips *d* and *e* to the cutting-shears.

G designates the stationary blade of the shears, fixed on a standard, *G'*, and *G²* designates the movable blade of the same, which is fixed on a rock-shaft, *G³*, that is journaled in the standard *G'* and in a standard, *G⁴*. A 70 ever, *G⁵*, is secured to the rock-shaft *G³* near the standard *G⁴*, and through said lever the rock-shaft receives motion from a vertically-moving portion of the folding devices.

Having thus briefly described the device for 75 feeding the wrapping material, I will now describe the frame-work of the wrapping devices and the manner in which the same may be adjusted to accommodate articles or packages of different size, and will then describe the 80 moving parts of the wrapping devices.

H H' H' H² H² designate six posts or pillars rising from the table *A* and joined together by cross-pieces *h h' h²*. Upon top of the cross-pieces *h h' h²* are laid two *T*-irons, 85 *I I'*, which extend from the shears to near the end of the table *A*. These two irons are secured upon top of the cross-pieces by means of laterally-projecting flat strips *i i*, having slots *i' i'* near their ends, through which pass 90 screws *i² i²*, that rise from the standards *H H* and *H' H'*, fitted with thumb-nuts *i³ i³*. By means of the slotted strips *i i* and the thumb-nuts *i³ i³* the distance apart of the irons *I I'* 95 may be readily adjusted and fixed, and, as these irons support and carry the adjustable portions of the frame-work of the wrapping devices, the whole adjustment of the frame is accomplished by loosening the thumb-nuts and moving the irons *I I'* together 100 or apart. From each of the irons *I I'*, near the rear end of the same, depend two vertical posts, *K K K K*, and to the insides of these posts are secured two metallic plates, *K' K'*, whose forward ends are spirally curved, the 105 curvature of the ends serving, as will presently appear, to form the last fold of the wrapping material upon the article or package, and the straight portions of these plates form the sides of the chute or passage through 110 which the wrapped articles are delivered from the machine.

K² designates a wide flat plate fixed horizontally between the vertical plates *K' K'* and forming a part of the top of delivery-chute 115 above referred to. The plate *K²* has a wide upturned end, *K³*, the lower edge of said plate being rounded off, as shown, and this upturned end serves as a shield and stationary folder, acting to fold down the horizontal flap 120 of the wrapper as the article is pushed under said plate. To the plate *K²* are secured two cross-bars, *k³ k³*, slotted near their ends and having uprights *K⁴ K⁴*, which fit into tubular sockets *k⁹ k⁹* on the under side of the cross-pieces *h h'*. Spiral springs may be arranged 125 within the tubular sockets *k⁹ k⁹*, and the said sockets and spiral springs serve to guide and sustain the top of the delivery-chute and permit the same to give if any of the articles 130 passing therethrough should be thicker than the others. To the said cross-bars *k³ k³* are secured by screws *k⁵ k⁵*, passing through the slots in said cross-bars, two plates, *k⁶ k⁶*, which

extend from just in the rear of the upturned end of the plate K² to the rear end of the same. Upon top of the plates k⁶ k⁶ are pins k⁷ k⁷, which pass through holes in lateral arms 5 k⁸ k⁸ on the standards or posts K K K K.

Upon a line with the curved ends of the vertical side plates, K' K', and affixed to the edges of the plates k⁶ k⁶, are two vertical ears, k² k², having their forward ends curved outwardly and their lower forward corners turned up slightly; said ears acting to turn in the last angle fold of the wrapping material, as shown at 4, Fig. 16.

The frame-work of the wrapping devices 15 above described is capable of being adjusted to accommodate different-sized articles or packages, as follows: The thumb-nuts i³ i³ and the screws k⁵ k⁵ being loosened, the irons I I' may be set farther apart or closer together 20 in their movement, carrying with them the vertical side plates, K' K', and the plates k⁶ k⁶, thus increasing or diminishing the width of the delivery-chute accordingly as said irons are moved closer together or farther apart. 25 The web of the irons I I' is turned in near the forward end of the same, and upon the outside of the web on each side is secured a block of metal, L, which is substantially triangular in cross-section. Upon top of the 30 block L is secured an arm, l, which projects upward and outwardly, and to said arm is attached a spring, l², to the other end of which is secured a plate of metal, l³, that passes through a slot, l¹, in the web of iron I. A 35 pin, l⁴, is fixed in the slanting under side of the block L, and in one position of the plate l³, as in Fig. 6, its outer edge bears against the said pin. The plate l³ has a pin, l⁶, on its bottom, that passes through a triangular or 40 wedge-shaped slot, m, in the head m' of a sliding plate, M. This plate M lies and slides upon the outside of the iron I, and is held in position by a screw, m², that passes into the web of the iron and through a slot, m³, in a 45 vertical flange, m⁴, near the end of the plate. Upon top of the flange m⁴ and at each end of the same is a lug, m⁵ m⁵, and a cross-head, N, upon a horizontally-reciprocating rod, N', contacts with these lugs alternately, thus imparting 50 an intermittent reciprocating motion to the side plates on each side. The plate l³ has a certain amount of lateral play in the slot l¹, and is capable of turning on the edge of said slot as on a pivot when its inner and lower 55 edge is pressed upwardly, and by this movement the plate is disengaged from the pin l⁴, and when so disengaged the spring l² draws the plate back until its inner edge is just on a line with the inner edge of the slot l¹. 60 The two positions of the plates l³ l³ are best seen in the detail views, Figs. 6 and 7, and the manner in which the same are operated is as follows: The plates l³ l³, being in the position shown in Fig. 6, receive and sustain the package to be wrapped until such time as a table, T, which rises up under the plates l³ l³ at certain regular intervals, contacts with said plates

and lifts their inner edges. This causes the plates to become disengaged from the pins l⁴, and they fly back into the position shown in Fig. 7, thus allowing the article to rest upon the wrapping material, which projects over said table. The table T and the plates l³ l³ are restored to their former position by the backward motion of the slide-plates M, the triangular slots m acting upon the pins l⁴ and forcing the plates out through the slots and until their rear edges again engage with the pins l⁴ l⁴.

O designates a flat horizontal apron which is placed in the rear of the pivoted plates l³ l³, and is secured to the inner edge of the T-iron on one side, projecting through an opening in the web of the iron on the other side and beneath the bottom of the chute P'. 85

P designates a second table which rests upon the cross-pieces h¹ h², and has a central rectangular cavity, p, that lies under ends of the irons I I'. This table P serves to receive and sustain the wrapping material as it is fed forward from the rolls, and at the side of the cavity p are arranged adjustable guides p' p', which hold the paper in position over the cavity p while the table is ascending.

In order to prevent the paper or other wrapping material from sagging down into the opening p in the table P, I provide two wire forks, p² p², which extend over said opening while the paper is being fed forward, and which are turned out of the way by appropriate mechanism when the paper is in proper position. These wire forks are fast to the tops of upright rods p³ p³, which are swiveled in the block p⁴, to which is hinged the first of the hinged plates g, which effect the folding 105 of the first flap of the wrapping material over the top of the article. These rods p³ p³ are square in cross-section, and are each given a quarter-turn, so that they form spirals, and they pass through square holes in arms p⁵ p⁵, 110 projecting from a cross-bar, p⁶, which is secured to the tops of vertically-reciprocating rods which carry the racks operating the folder Q, the result of which arrangement is that upon the downward movement of the 115 cross-bar p⁶ the wire forks p² p² are turned aside from over the opening p, and upon the upward movement of the same the wires are restored to their original position.

One of the features of the present device 120 to which I will here call particular attention is that the weight of the article to be wrapped is utilized to effect a portion of folding of the wrapper, and this is effected by having the article descend through the opening p in the 125 plate P, taking down with it the two sheets of wrapping material which have been previously cut from the strips d and e and folding up the sides of the same against the sides of said opening. The table T, which has been 130 previously referred to and described as ascending beneath the plates l³ l³, and after operating the same receiving the article to be wrapped and the wrapping material, con-

sists of a flat plate mounted upon a vertical post or standard, t , that is connected by a pitman, t' , with the gear-wheel t^2 , which receives motion from the mutilated gear B^2 on the 5 main shaft B, the table being thus operated by the same mechanism which in the machine described in my before-mentioned patent operated the tilting-trough and its plunger.

It being premised that the folding devices 10 are substantially the same as those described in my aforesaid patent, it will be unnecessary to particularly describe the same; but I will now describe the means whereby said folding devices may be adjusted to operate upon packages of different sizes.

It will be seen that what I call the "end-wing folders," which are marked R R in the drawings, are hinged to a skeleton frame composed of the cross-bars $R^2 R^3$ and vertical rods 20 $R^4 R^4$, which reciprocate through holes in the table, the cross-bar R^3 carrying an anti-friction roller, r^5 , which travels in a cam-groove, S^8 , in the wheel B' . Another and similar frame composed of vertical posts $s^2 s^2$ and 25 cross-bar U^4 , the latter carrying a roller, v^5 , which engages with a cam-groove, v^6 , in the wheel B' , is provided at its upper end with the vertical racks $s s$, which engage with toothed segments $S S$, fixed to the pintles of 30 the folding wings R R, which latter are operated by the engagement and co-operation of the racks and segments, while the frames are operated in a differential manner under conditions and for the purpose designated in my 35 patent already referred to. The rock-shaft G^3 , which actuates the shears, receives motion from the frame $R^2 R^3$ through a vertical rod, g^5 , connected to the bar R^2 .

In Fig. 8 of the drawings I have illustrated 40 the end-wing folders and the means for adjusting the same. The said end-wing folders, which are lettered R R, are hinged to sliding blocks $r r$, dovetailed into slots in the plate r' and having on top and at their inner 45 ends lugs $r^2 r^2$. The plate r' is formed with a piece, r^3 , which is in line with the lugs $r^2 r^2$, and the lugs $r^2 r^2$ are formed with reverse screw-threads, so as to receive a right and left screw, r^4 , which passes through them and 50 through the piece r^3 . The screw turns in the piece r^3 without traveling, and a jam-screw, r^6 , serves to fasten the screw r^3 when the proper adjustment has been secured. As the toothed sections $S S$, by means of which the plates R 55 R are turned, are fast on the pintle of said plates, it is necessary to provide for the difference in position of the same, and accordingly I mount the racks $s s$, with which the sections engage, upon arms $s' s'$, which pass 60 through slots in the head of the vertically-movable rods $s^2 s^2$, through which said racks receive motion from the cam-wheel B' and secure the arms in the slots by means of keys $s^5 s^5$, as shown.

65 The horizontally-swinging side-angle folders are constructed and operate substantially in the manner shown and described in my pre-

vious application, but are made adjustable by the following arrangement of devices:

The folders consist of the horizontally-swinging arms W W, which are secured at their outer ends to short vertical shafts $n n$, which pass through slots $a^5 a^5$ in table A and are journaled in blocks $n' n'$, which move in dovetailed grooves in the table, the said blocks 75 being adjustable toward and from the edge of the table by screws $n^2 n^2$. To the lower ends of the shafts $n n$ are secured arms $n^3 n^3$, which have friction-rollers $n^4 n^4$, that work in slots $n^5 n^5$ in a frame, W' , which is mounted on a 80 horizontally-reciprocating rod, W^2 , which receives motion from the cam on the periphery of the wheel B' . The rod W^2 is utilized for the purpose of giving motion to the rod N' , which carries the cross-head and the plunger 85 N^2 , projecting out beyond the end of the table A and connected to said rod by a frame, W^3 .

Operation: The article to be wrapped (which is, for instance, a cake of soap) is fed to the table O by the chute P', and is slid forward 90 upon the supporting-plates $l^3 l^3$ by the plunger N^2 . At the same time the two strips $d e$ have been fed forward (the lower strip a somewhat greater distance than the other) below the cake of soap, a proper length being cut off by the 95 shears. The forks $p^2 p^2$ have been utilized to sustain and guide the wrapping material, and are now turned aside out of the way. The table T, arising, releases the plates $l^3 l^3$, and the soap and the wrapping material descend and 100 rest upon the table T. The latter now descends, and the two sides of the wrapper are folded up into vertical position, as seen at Fig. 16, by contacting with the sides of the opening p in table P. The table T continues 105 its descent until its surface is level with the surface of table A. The folder Q now comes into play and folds down the wrapping material at one side, as seen at 2, Fig. 16. A plunger, V, that receives motion by means of V' from the cam upon the periphery of cam-wheel B^3 , now pushes the article along beneath the end of plate K^2 , and the wrapping material on the other side of the soap is thereby folded down over the top. The end-wing folders now come 115 into play, and the package assumes the shape shown at 3, Fig. 16, and then the movable side-angle folders W W, the package then appearing as at 4, Fig. 16. The article is then pushed still farther under the plate K^2 by the 120 plunger V, and the stationary side-angle folders give it the shape shown at 5, Fig. 16, and the curved ends of the vertical plates $K^2 K'$ complete the folding operation. The parts 125 now return to their former position, and the next article is operated upon in like manner.

The manner of adjusting the several parts of the machine has been hereinbefore sufficiently described and need not be repeated.

Having described my invention, I claim— 130

1. In a package-wrapping machine provided with a paper-cutting instrument, substantially as described, and a series of paper-folding wings, the combination, with said cutting-in-

- strument and folding wings, of two separate and independent reel-shafts, from which the paper is fed to the wrapping devices, and two sets of feeding-rolls, between and by which the paper is fed, with mechanism, substantially as described, whereby said sets of feeding-rolls are intermittently rotated at different rates of speed respectively.
2. In a package-wrapping machine, the combination, with the devices, substantially as described, for supplying the wrapping material in proper sections and the mechanism, substantially as described, for folding the same around the article to be wrapped, of the plates $b^3 b^3$, adapted to temporarily sustain the article above the wrapping material, and the vertically-movable table T, adapted to release said plates and to receive the article and the wrapping material, substantially as described.
3. In an organized package-wrapping machine, the combination, with the devices, substantially as described, for feeding the wrapping material and the mechanism, substantially as described, for folding the same upon the article to be wrapped, of the plates $b^3 b^3$, mounted in the framing of the machine, and the mechanism for projecting said plates into position to receive and sustain the article to be wrapped and for retracting the same, substantially as described.
4. In a package-wrapping machine, the combination, with devices for feeding paper and articles to be wrapped in the same, of a series of reciprocating folding wings adjustable, substantially as described, so as to be capable of folding wrappers upon articles of different sizes, as set forth.
5. In a machine for wrapping packages or articles, the combination, with the base A, pillars H H' H², and cross-bars h h' h², of the T-irons I I', supported upon said cross-bars and laterally adjustable on the same, the ver-

tical side plates, K' K', connected to said irons by vertical posts K K and adjustable therewith, substantially as described.

45

6. In a package-wrapping machine, the combination, with the irons I I' and the plates $b^3 b^3$, projecting through slots $b^4 b^4$ in the webs of said irons and having pins $b^6 b^6$, of the horizontally-movable slide-plates M M, having triangular slots $m m$, the springs $b^2 b^2$, and the pins $b^5 b^5$, all constructed and arranged substantially as and for the purpose described.

7. In a package-wrapping machine, the combination, with the table P, having an opening, p, for the passage of the article to be wrapped, of the forks $p^2 p^2$, the swiveled rods $p^3 p^3$, having spiral stems, the arms $p^5 p^5$, working on said rods, and the vertically-moving cross-bar p^6 , carrying said nuts, substantially as described.

8. In a package-wrapping machine, the combination, with the plate r' and the sliding blocks r r, of the end-wing folders R R, hinged to said blocks, and the screw r⁴, passing through lugs on the blocks and operating to adjust the same, substantially as described.

9. In an organized package-wrapping machine, the combination, with the table A, having slots $a^5 a^5$, and the horizontally-moving frame W', having slots $n^5 n^5$, of the blocks n' n', the swinging folders W W, and the arms $n^3 n^3$, secured to vertical shafts n n, journaled in said blocks, and the adjusting-screws $n^2 n^2$, all constructed and arranged substantially as described.

In testimony that I claim the foregoing I have hereunto set my hand this 22d day of March, 1887.

WALTER S. JARBOE.
